UNITED STATES PATENT OFFICE.

SAMUEL J. WALASCHEK, OF NEW YORK, N. Y.

COMBINATION TABLE AND PICTURE ALBUM.

Application filed June 25, 1923. Serial No. 647,472.

To all whom it may concern:

Be it known that I, SAMUEL J. WALASCHEK, a citizen of the United States, residing at New York, in the county of Bronx and State of New York, have invented certain new and useful Improvements in a Combination Table and Picture Album, of which the following is a specification.

My invention relates to new and useful improvements in tables, and has associated therewith a highly novel form of picture album, the primary object thereof residing in the provision of such a table wherein the top is constructed to afford a compartment for a series of picture frames, wherein the same are readily movable within the compartment for allowing the pictures within any one of the frames to be readily viewed when a hinged section of the table top is raised.

An additional object of my invention resides in the provision of such a table with which is associated a picture album wherein the same is extremely simple of construction, and one that may be manufactured and marketed at relatively small cost.

Yet another object is to provide such an article wherein the same may be employed for all purposes that an ordinary table is now used, and wherein the picture album within the compartment formed in the table top may be operated in a novel, simple and expeditious manner.

An additional object resides in the provision of such a table wherein the different picture frames comprising the album within said compartment of the table top are so mounted therewith as to be freely movable towards and away from an opening provided in the table for viewing the pictures within the frames.

The nature and advantages of the invention will be better understood when the following detailed description is read in connection with the accompanying drawings, the invention residing in the construction, combination, and arrangement of parts as claimed.

In the drawings forming part of this application, like numerals of reference indicate similar parts in the several views, and wherein:

Figure 1 is a side elevation of my improved combination table and picture album.

Figure 2 is a detail longitudinal vertical cross sectional view of the table top per se,

for more adequately disclosing the position of the picture album therein.

Figure 3 is a top plan view of the table with the cover plate removed.

Figure 4 is a fragmentary cross sectional view similar to Figure 2, but taken through a different point of the table top, for disclosing more clearly the operating mechanism of the picture album, and

Figure 5 is a perspective of one of the picture frames included in the album.

Now, having particular reference to the drawings, my novel table embodies generally, a desirable form of base 5, a single leg 6 and a top 7.

My invention per se, has relation to the specific form of the said table top 7, which embodies a bottom wall 8, preferably of octagon shape, side walls 9, and an octagon shaped top 10, spaced above said bottom wall, and being hingedly secured at 12 to a convenient point of the side wall 9, it being noticed from a consideration of Figures 1, 2 and 4 that the top 11 has its marginal edges projecting beyond the side walls of the top, and that such a construction provides a compartment between said top and bottom walls.

Upon the inner face of the bottom wall 8 and centrally thereof is a bearing disk 13, that is formed with a central opening coextensive with a screw threaded socket in said bottom wall. In face to face contact with this bearing disk 13 is a similar bearing disk 14, that is embedded in the surface of a relatively large circular plate 15 within the compartment, formed by the particular construction of said table top. Upon the top surface of the plate 15 and centrally thereof is a star plate 16, that is formed with a central opening, which is surrounded by a boss 17 and extending through this opening as well as coextensive openings within the plate 15 and disk 14 is a wood screw 18, whereby the said plate 15 has free rotation within the table compartment.

Upon the said plate 15 is a desirable number of metallic U-shaped frames 19 that are arranged with relation to each other, as shown in Figure 3. Pivotal secured within each of these frames 19 at the rear end thereof is a pair of picture carriers 20 and 21, respectively, that are adapted for normally positioning within said frames 19 as clearly shown in Figure 2. As shown in Figure 5, each of these picture carriers

include an inner and outer plate element 22 and 23, between which pictures 24 are to be positioned, it being of course understood that said plates 22 and 23 are formed with openings, whereby said pictures may be viewed, and in this instance, it might be well to note that the plates comprising some of the picture carriers are to be provided with a pair of openings for displaying a pair of pictures, while others are formed with but a single opening for displaying pictures of family groups, etc. Said plates 22 and 23 constituting the picture carriers are to be maintained closed by a suitable latch element 25, it being of course understood that by releasing the latch, the plate may be opened with respect to each other for the insertion of the pictures.

20 Pivotal secured at 26 to a point off center of the bottom wall 8 of the table top, and having free swinging movement within a bevelled portion 27 of said bottom wall is a spring arm 28. This arm 28 is of such a length as to project through a slot 29 within the side walls of the table top, and coextensive with the said bevelled portion 27 of the bottom wall 8. The free end of said arm 28 carries an operating knob 30, and formed upon said arm at a point within the compartment of the table top is a lug 31, that is shouldered at its outer edge as shown in Figure 4. Secured to the side walls of the table top within the compartment directly above said slot 29 and of a length equivalent to said slot is a plate 32, that is formed at its lower edge with an inwardly directed arcuate flange 33 of lesser length than said slot 29, and upon which the said shoulder of the lug 31 rides when it is desired to rotate the picture frame carrying plate 15. The edge of this picture carrying plate 15 is formed at points between the different picture carriers 19 with notches 34, for the reception of the lug 31 of the spring arm 28, whereby this plate may be rotated by a swinging movement of the arm upon its pivot. It will of course be understood that when the picture carrying plate 15 has been moved a distance equivalent to the length of the slot 29 by the spring arm 28, this arm may be forced downwardly for engaging the shoulder of the lug 31 beneath the arcuate flange 33 of said plate 32, for permitting a reversal of movement of the arm without a consequent reversal movement of said picture carrying plate 15.

60 At one side of the slot 29, the top wall of the table top 7 is formed with an opening within which is a hinged section 11', adapted to be moved to the dotted line position of Figure 2, whereby the pictures of the album may be viewed. The inner side of this section 11' carries a mirror 35 for

obvious purposes. The side 9 of the table top is formed with a cut out portion directly beneath the cut out of the top wall 11 of said table top 7, and hingedly secured within this cut out is a side wall section 36, that is adapted to be moved to the dotted line position of Figure 2, whenever access is desired to the different picture frames of the carrier 19. This section 36 carries a desirable form of lock 37, whereby this section 36 and the table top section 11' may be secured together.

70 The said top section 11' carries pendent brackets 38, that are formed with openings for receiving screws 39 that project through openings in the side wall 9 of the table top 7 for maintaining the top wall 11 of said table top in the closed position of Figure 2.

75 In view of the above specification when considered in conjunction with the accompanying drawings, numerous advantages of a combined table and picture album of the present type will be fully appreciated by those skilled in the art, and even though I have herein set forth that the table consists of a specific design, it is nevertheless to be understood that I do not wish to be limited to such a design of table.

80 In addition, it is also to be understood that while I have herein shown and described the preferred embodiment of the present invention, minor changes may be made therein, without departing from the spirit and scope of the invention as claimed.

85 Having thus described my invention, what I claim as new, and desire to secure by Letters Patent, is:

90 1. A device of the class described including a housing having a bottom, side walls extending from and above said bottom, and a table top hingedly connected at one side to said side walls co-extensive with the bottom for enclosing the space between the side walls, a plate rotatably mounted on the bottom within the housing, a plurality of 95 U-shaped frame members disposed in edge-wise relation on said plate and arranged in spaced relation on the edge portion thereof, a plurality of picture holders hingedly mounted in each U-shaped member in superposed relation, and means for rotating said plate for presenting said U-shaped frame members at a desired point in said housing whereby said picture frames may be moved on their hinges for viewing the pictures 100 carried thereby.

105 2. An article of the class described including a table top portion having a housing provided with a bottom wall, side walls, and a table top hingedly connected to said side walls, said top having a section thereof hingedly connected to the remaining portion and foldable thereon to provide access to the interior of the housing, a plate rotatable in said housing, a plurality of U-shaped 110

frame members arranged in spaced relation on said plate and having the free ends extending outwardly and terminating adjacent the edge of the plate, a plurality of 5 picture holders hingedly mounted in said U-shaped frame members, each picture holder including a pair of relatively movable members adapted for interfitting relation and providing with picture viewing 10 openings, and means for holding said members in interfitting relation whereby pic-

tures may be secured therebetween to be viewed through said openings therein, and means for rotating said plate so that the U-shaped frame member may be successively 15 positioned under the hinge section of the table top so that the pictures carried in the picture holders hinged in said member may be viewed.

In testimony whereof I affix my signature. 20

SAMUEL J. WALASCHEK.
